(57) CLAIM

The ornamental design for a cosmetics bag, as shown and described.

DESCRIPTION

FIG. 1 is a perspective view of a cosmetics bag showing my new design;

FIG. 2 is a side view of the cosmetics bag shown in FIG. 1; and,

FIG. 3 is a top view of the cosmetics bag shown in FIG. 1. The surfaces of portions of the article not shown in the drawing or described in the specification form no part of the claimed design.

1 Claim, 2 Drawing Sheets

FIG. 1

FIG. 2
